SHEET FEEDING MACHINE

Leonard H. Cross, Port Washington, N. Y., assignor to Cross Paper Feeder Company, Boston, Mass., a corporation of Massachusetts

Application March 18, 1936, Serial No. 69,431

15 Claims. (CL 271—38)

The present invention relates to improvements in the type of sheet feeding machines in which a bank or pile of sheets is fed forwardly upon a feed board in partially separated or feathered out condition. The bank of partially separated or feathered out sheets in this type of machine is intermittently fed or moved forwardly upon the feed board by suitable mechanism automatically thrown into and out of action by suitable controlling devices which have for their purpose the substantially continuous presentation of the feathered out bank in proper position upon the feed board for the action of suitable final separating and feed-off devices.

It has heretofore been proposed to control the feed or forward movement of the feathered out bank of sheets in this type of machine in various ways such for instance in those machines embodying combing separators for the final separation of the top sheets by means of the combing intervals, the feed being thrown into action through suitable means when the combing interval exceeds the predetermined amount or thrown out of action when the combing interval is less than the normal period; or the control of the bank feed has been effected by means of sheet actuated devices of various forms engaged by the front of the feathered bank of sheets; or in some cases the bank feed has been controlled by means of caliper devices which engage the forward portion of a feathered out bank for throwing the feeding mechanism into or out of action upon the increase or decrease from normal of the thickness of the bank at the point of operation of the caliper.

The present invention is an improvement upon this same general type of continuous sheet feeding machine and consists of means for feeding or advancing a feathered out bank or pile of sheets upon the feed board in combination with final separating and feed-off devices and means for throwing the bank feed into action or out of action controlled by the extent of movement of the feed-off devices in carrying a finally separated sheet from the feathered out bank to sheet delivery mechanism of any suitable form. The feed-off devices are controlled by means actuated by the advanced sheet for arresting their movement upon the delivery of the sheet to the delivery mechanism.

In carrying out the present invention I prefer to embody the same in a continuous sheet feeding machine of the double table type such as shown in the patent of Frank L. Cross and

1930, in which machine the bank of sheets is feathered or fanned out in its movement from the supply table to the feed board through the pile reversing throat, and the feathered bank is intermittently held against motion on the delivery feed board while the top sheet of the bank is separated at its rear edge to receive a film of air from suitable air blast devices and, after this preliminary separation, the front edge of the sheet, floating upon a film of air, is grasped by feed-off grippers which first raise said front edge away from the feathered out bank and then move in a higher plane away from the bank and present the sheet to drop roller delivery mechanism.

In the application of the present invention to the machine of this Cross and Hallstream Patent No. 1,760,119, I employ control mechanism for throwing the bank feed into and out of operation, the bank feed being thrown into operation or held out of operation depending upon the extent of movement of the feed-off devices in carrying separated sheets from the fanned out bank to the drop roller delivery mechanism. It will be understood that the extent of this delivery movement of the feed-off devices terminated by the sheet actuated cut-out trips, will always be dependent upon the location of the forward edge of the top sheet of the fanned out bank upon the feed board with relation to the delivery mechanism.

In order that the invention may be fully understood it will first be described with reference to the accompanying drawings and the novelty afterwards more particularly pointed out in the annexed claims.

In said drawings,

Figure 1 is a side elevation of a sheet separating and delivery machine of the double table type embodying the present invention;

Figure 2 is a detail vertical longitudinal sectional view of the delivery part of the machine showing the bank feeding mechanism under the control of the sheet feed-off devices;

Figure 3 is a partial plan view of the essential parts of the mechanism shown in Figure 2;

Figures 4 and 5 are detail sectional views similar to Figure 2 showing different positions of the feed-off control of the bank feeding mechanism;

Figure 6 is a detail vertical longitudinal sectional view showing a modified form of the feed-off devices for controlling the bank feeding mechanism; and

Figure 7 is a view similar to Figure 6 showing the parts in a shifted position.

In the drawings the invention is shown embodied in a sheet feeder of the "continuous" type in which a bank of feathered or fanned out sheets is fed from an upper supply table 1 through a bank reversing throat 2 around a large feed roller 3 on to the lower feed table 4, by means of upper feed belts 5 and lower feed belts 6 arranged in the usual manner and intermittently driven by ratchet and pawl mechanism acting upon the lower belts 6 as will presently be described. The bank is further feathered or fanned out in passing around roller 3 from the upper to the lower table. The feed table 4 has the upper runs of the usual lower belts 6 extending over a large part of its length. The feathered bank rests upon these feed belts 5 and 6 by which the successive top sheets are presented in position for the action of the feed-off devices which move the sheets individually from the pile on the feed table 4 to the delivery mechanism.

The delivery end of these bank feeding belts 6 pass around the usual belt pulleys 7 carried by a transverse shaft 8 suitably journaled in the machine frame beneath table 4. The pulley shaft 8 carries a ratchet wheel 8a engaged by a feeding pawl 9 pivotally mounted upon a lever 10 which is journaled upon the shaft 8, the feed pawl 9 being held yieldingly in engagement with the ratchet wheel by means of a spring 11. The end of the lever 10 opposite to the pawl 9 is connected through a link 12 with the lower end of an automatically controlled cam operated lever 13 journaled upon a stud shaft 14 and projecting above the feed board 4 at one side of the machine into position beneath its operating cam. This lever 13 carries an antifriction roller 15 presented in the vertical plane of a feed operating cam 16 splined upon the cam shaft 17 of the machine. The shape of the cam 16 is such as to impart motion to the lever 13 once every revolution for imparting a feeding stroke to the belt feeding ratchet when permitted to do so by the controlling mechanism hereinafter described. A spring 18 acts upon the lever 13 to retract the pawl-carrying lever 10 and present the roller 15 in the path of the cam 16.

It will be understood that the improved machine is preferably equipped with suitable mechanism for effecting the preliminary separation of the rear ends of the successive top sheets of the feathered pile and winding the sheets, any suitable means, such as fully set forth in said Cross and Hallstream Patent No. 1,760,119, and indicated at X in Figure 1 in being employed for this purpose. The general arrangement only of such separating means is illustrated in Figure 1 of the drawings.

The delivery mechanism for the machine is preferably of the drop roller type in which the continually rotating lower feed rollers 20 upon a shaft 21 are presented with their upper periphery in the plane of feed while the upper drop rollers 22 journaled upon rock arms 23 extending from a rock shaft 24 are adapted to peripherally engage the forward edge of a sheet above the feed rollers 20 and feed the same from the bank upon the feed board in a well-known manner.

Any suitable feed-off devices may be employed for conveying separated sheets from the feed board to the drop-roller delivery mechanism. In the preferred form of the improved machine I

employ suction cup grippers, one of which is indicated at 25 mounted by bracket 26 upon the vertical face of a reciprocating feed bar 27 which is supported by and slides in a guide bracket 28 carried by a lever 29 journalled upon a stud 30 projecting laterally from an auxiliary machine frame 31. This bracket supporting lever 29 carries upon its rear end an antifriction roller 32 presented in the vertical plane of a controlling cam 33 splined upon the cam shaft 17 whereby in the rotation of said cam the delivery end of the sliding feed bar 27 is intermittently raised and lowered.

The rear end of the feed bar 27 is pivotally connected and supported at 34 upon the lower end of an operating lever 35 pivotally mounted upon an auxiliary machine frame at 36 and connected at 37 with a link 38 which has a forked forward end straddling the cam shaft 17 and carrying an antifriction roller 39 which operates in peripheral engagement with a cam 40 upon the cam shaft 17. A spring 41 connects lever 35 with the machine frame for holding the antifriction roller 39 in engagement with cam 40 for effecting the forward and backward movements of the feed bar 27.

The feed bar 27 is formed upon its upper edge with ratchet teeth 27a and a cut-out pawl 42 is mounted upon a stud 43 of bracket 28 to engage said ratchet for arresting the spring induced motion of the feed bar toward the delivery end of the machine. There is a cam heel 44 projecting beneath the cut-out pawl 42 and a pin 45 projecting laterally from the feed bar 27 in position to engage the cam heel 44 and raise the pawl 42 out of engagement with the ratchet 27a upon the completion of movement of the feed bar rearwardly in preparation for the succeeding feeding movement of the feed bar, see Figure 4.

A cam shaped controlling finger 46 pivoted to the bracket 28 at 47 projects upwardly beneath the cut-out pawl 42, a spring 48 connecting the finger 46 with pawl 42 to yieldingly hold them in their respective positions, in which the end of pawl 42 rests upon finger 46 and is supported disengaged from the ratchet 27a. 49 is a cut-out trip finger pivoted at 50 to the bracket 28 and supported adjacent to one of the lower feed rollers 20 to intersect the path of sheets from the feed board over the rollers 20. This trip finger 49 carries an adjustable screw 51 that passes loosely through a perforation in the finger 46 and supports a small coil spring 51a between members 46 and 49, so that the latter, when tripped by a sheet, rocks member 46 to lower the dog 42 into engagement with the ratchet 27a for arresting the delivery movement of the feed-off gripper 25. Any suitable form of cut-out trip and dog may be used.

It will be understood without illustration that two parallel sets of feed-off devices with their independent cut-outs are employed as is usual in this type of machine.

Returning to the mechanism for intermittently feeding the bank of feathered sheets upon the feed board it will be observed that the operating lever 13 is formed upon its upper end with a series of steps or shoulders 52 with which engages a dog 53 splined upon a transverse pivot shaft 54 journalled in suitable bracket bearings upon the machine frame and having adjustably mounted upon it a tappet arm 55 presented in the path of an adjustable screw tappet 56 threaded through a lug 57 on the face of the 75

lever 35 above referred to. The successive steps or shoulders 52 are progressive radial distances from the pivot 14 of lever 13 so that the particular step or shoulder engaged by dog 53 on the retraction of lever 13 after a bank feeding stroke will depend upon the extent of movement of the feed-off gripper slide indicated by raising dog 53 more or less. It will be observed that so long as the tappet arm 55 is free from the pressure of the tappet screw 56 the dog 53 will engage one of the steps or shoulders 52 and thereby prevent the retraction of the ratchet operating lever 13 and pawl 9. In the forward movement of the feed bar 21 carrying the feed-off suction gripper 25 the tappet screw 56 engages tappet arm 55 and disengages dog 53 so as to allow lever 13 and pawl 9 to be retracted as the low part of cam 16 reaches antifriction roller 15. The extent of retraction of this operating mechanism depends upon the extent of movement of the feed-off devices which is controlled by the sheet actuated cut-out dog 42.

Considering the machine in the position shown in Figure 4 it will be observed that the operating lever 13 for the bank feed is held in its extreme position at the completion of a feeding stroke, the dog 53 engaging the lowest step or shoulder on the lever. This position results from the previous feeding stroke of the cam, the dog having been freed to its engaging position by the rearward movement of lever 35. It will also be observed that in this rearward stroke of the mechanism the pawl 42 is held up out of engagement with the ratchet 21a by reason of the engagement of pin 45 with cam arm 44. It will also be observed that the delivery end of the feed bar 21 is in its elevated position and the suction gripper is in its rearmost position. The parts are shown as they are about to move for another operation, the movement being from the position shown in Figure 4 to that shown in Figure 2, the suction gripper being lowered by reason of the lowering of the delivery end of feed bar 21 and as the feed bar moves toward its delivery end carrying with it a gripped sheet. The tappet 56 engages the arm 55 controlling dog 53. If the movement shown in Figure 2 is sufficient to place the sheet in delivery position beneath the drop rollers, there will be no movement of the operating mechanism for the bank feed. If, however, the feed-off devices have to move a little further it will be observed that the dog 53 will be raised out of the path of the lowest step or shoulder into the path of the next step or shoulder or in extreme conditions entirely free of the shoulders so that the antifriction roller 15 will be moved by spring 18 into engagement with the lowest part of the controlling cam 16 ready to be actuated for a complete feeding stroke of the ratchet mechanism of the bank feed. This extreme position is shown in Figure 5 in readiness for a bank feeding stroke. In this same position the feeding stroke of the feed bar has been arrested by the engagement of the pawl 42 which was dropped by the sheet actuated cut-out removing the guard 46, its engagement with the pawl having been broken by the sheet actuated cut-out. The suction gripper then releases the sheet with the action of the drop roller delivery mechanism which quickly feeds the sheet off from the path while the feed-off devices are raised away from the sheet and returned to their initial rearward position illustrated in Figure 4.

In operating under certain conditions it is de-

sirable to employ positive grippers with the feed-off devices, such for instance as is shown in the modification of Figures 6 and 7 of the drawings. In these illustrations of the form of device with positive gripper, there is shown the feed slide 5 with conventional suction gripper which will act the same as in the preferred form of the mechanism and in addition a positive gripper that cooperates with the suction gripper. In this form of device the ratchet feed slide 21 has secured to its delivery end a bracket plate 55 on which is formed a downwardly and forwardly projecting arm 56 having a laterally projecting finger 56a which constitutes the upper fixed jaw of a positive gripper. Pivotedly mounted to the feed bar 21 adjacent to bracket 55 is the movable jaw of the gripper comprising a plate 57 formed with a lower gripper jaw 58 spaced from the main body of plate 57 by a recess 59 to fit over the fixed gripper jaw 56a when it is swung into position to grip the forward edge of a sheet between jaws 56 and 58. This gripper plate 57 has an elongated slot in its upper end lengthwise of the gripper plate as indicated at 60, in which engages the pivot pin 61 projecting from the ratchet bar 21, the purpose being to permit the gripper plate 57 to not only swing upon pin 61, but also to move lengthwise upon the pin to bring the movable gripper jaw 58 into clamping engagement with fixed gripper jaw 56a upon the forward edge of a sheet that is to be taken from the feed board to the delivery mechanism.

62 and 63 are toggle links pivotally mounted respectively upon the pivot pin 61 and upon a pin 64 projecting from the face of gripper plate 57. These toggle links 62 and 63 are also pivotally connected together at their inner adjacent ends, the connecting pivot also uniting them to a link 65. A stop pin 67 upon gripper plate 57 limits the movement of toggle links 62, 63 in toggle 40 straightening direction induced by the spring 66, connecting link 63 with pin 65a on gripper plate 57. The link 65 connects at its rear end 68 with a bell crank lever 69 pivotally mounted at 70 upon a bracket 71 rigidly secured to and projecting up from the ratchet feed bar 21. This bell crank lever 69 carries an antifriction roller 72 operating in peripheral engagement with a gripper controlling cam 73 keyed to the cam shaft 17. A spring 74 connects bell crank lever 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850

The illustration of the positive gripper mechanism in Figures 6 and 7 is simplified by omitting from these views the complete cut-out control of the feed slide, the dog 42 being, however, indicated so that it will be understood that the feed bar 21 is operated and automatically controlled in the same manner as described with reference to the preferred form of the mechanism.

In the action of the feed-off devices with positive delivery grippers it will be understood that the suction grippers 25 first raise the forward end of the top sheet from the feathered pile as indicated in Figure 6 and the positive grippers are immediately thereafter brought into position to grip the forward edge of the sheet as shown in Figure 7. The feed bar then moves forwardly until arrested by the automatic control when the gripper releases the sheet and is taken by the drop roller delivery mechanism.

No attempt has been made to illustrate the control of the air suction in the suction gripper since this is well-known practice in the art and it being a matter of mechanical skill to control the operation of the suction to suit the desired purpose. It is immaterial whether the suction gripper retains its hold upon the sheet after the positive gripper has taken hold of the sheet, the main function of the gripper in this modified form shown in Figures 6 and 7 being to raise the forward edge of the top sheet into position to be taken by the positive grippers.

The importance of the present invention is due to its simplicity and effectiveness in controlling the feed of the bank of sheets to exactly meet the requirements of the feed-off and delivery mechanisms. The control of the bank feed is more directly related to the requirements of the feed-off devices than have been the controls heretofore employed—the operation and extent of the bank feed being in direct relation to the extent of movement required of the feed-off devices in moving sheets from the feed board to the delivery mechanism. The improvement affords more time than heretofore to satisfactorily perform the bank feeding operation, since there is a longer period between the passage of the rear edge of the fed off sheet and the start of the feed-off of the next succeeding sheet.

The bank feeding mechanism is thrown into action whenever the feed-off devices move more than the normal distance in conveying the leading edge of a sheet to the drop roller delivery mechanism, and each time it is thrown into action, said bank feeding mechanism operates to the required extent to advance the bank to proper normal position upon the feed table, which position requires only the normal extent of movement of the feed-off devices.

I claim:—

1. In a machine for feeding sheets, the combination with a sheet support, and mechanism for advancing a bank of sheets upon said sheet support, of sheet delivery mechanism, feed-off devices adapted to move successive sheets from the bank to said delivery mechanism, and means actuated by the movement of the feed-off devices for controlling the bank advancing mechanism.

2. In a machine for feeding sheets, the combination with a sheet support, mechanism for advancing a bank of sheets upon said sheet support, means for separating successive top sheets from said bank, sheet delivery mechanism, and feed-off devices adapted to move separated sheets from the bank to said delivery mechanism, of means actuated by the movement of the feed-off devices for controlling the bank advancing mechanism.

3. In a machine for feeding sheets, the combination with a feed board, mechanism for advancing a bank of sheets upon said feed board, means for separating successive top sheets from said bank, sheet delivery mechanism, and sheet

controlled feed-off devices adapted to move successive separated sheets from the feed board to said delivery mechanism, of means actuated by the movement of the feed-off devices for controlling the bank advancing mechanism.

4. In a machine for feeding sheets, the combination with a feed board, mechanism for advancing a bank of feathered sheets upon said feed board, means for separating successive top sheets from the feathered bank, sheet delivery mechanism, and feed-off devices adapted to advance successive separated sheets from the bank to said delivery mechanism, of means controlled by the advance sheet for arresting the movement of said feed-off devices, and means actuated by the movement of the feed-off devices for controlling the bank advancing mechanism.

5. In a machine for feeding sheets, the combination with a sheet support, mechanism for advancing a bank of sheets upon said sheet support, means for separating successive top sheets from said bank, suitable sheet delivery mechanism, and feed-off devices adapted to move successive separated sheets from the bank to the delivery mechanism, of means actuated variably in accordance with the extent of movement of the feed-off devices for controlling the bank advancing mechanism.

6. In a machine for feeding sheets, the combination with a sheet support, mechanism for advancing a bank of feathered sheets upon said sheet support, means for separating successive top sheets from said feathered bank, drop roller delivery mechanism, and sheet controlled feed-off devices adapted to move successive separated sheets from the bank to the delivery mechanism, of means actuated variably in accordance with the extent of movement of the feed-off devices for controlling the bank advancing mechanism.

7. In a machine for feeding sheets, the combination with a sheet support, mechanism for advancing a bank of feathered sheets upon said sheet support, means for separating successive top sheets from the feathered bank, sheet delivery mechanism, and feed-off devices adapted to move successive separated sheets from the bank to the delivery mechanism, of means actuated variably in accordance with the extent of movement of the feed-off devices for controlling and determining the extent of operation of the bank feeding mechanism.

8. In a machine for feeding sheets, the combination with a feed board, mechanism for advancing a bank of feathered sheets upon said feed board, means for separating successive top sheets from the feathered bank, a drop roller delivery mechanism, and feed-off devices adapted to advance successive separated sheets from the bank to the delivery mechanism, of means controlled by the advanced sheet for arresting the movement of said feed-off devices, and means actuated variably in accordance with the extent of movement of the feed-off devices for determining the operation of the bank feeding mechanism.

9. In a machine for feeding sheets, the combination with a sheet support, mechanism for feathering and advancing a bank of sheets upon said support, means for separating successive top sheets from the feathered bank, sheet delivery mechanism, and feed-off devices adapted to move successive separated sheets from the bank to the delivery mechanism, of means actuated by the movement of the feed-off devices for 70 75

controlling the bank feathering and advancing mechanism.

10. In a machine for feeding sheets, the combination with a sheet support, mechanism for feathering and advancing a bank of sheets upon said support, means for separating successive top sheets from the feathered bank, sheet delivery mechanism, and sheet controlled feed-off devices adapted to move successive separated sheets from the bank to the delivery mechanism, of means actuated variably in accordance with the extent of movement of the feed-off devices for controlling and determining the extent of operation of the bank feathering and advancing mechanism.

11. In a machine for feeding sheets, the combination with a feed board, mechanism for advancing a bank of feathered sheets upon said feed board, means for separating successive sheets from the feathered bank, sheet delivery mechanism, and feed-off devices adapted to move successive sheets from the bank to said delivery mechanism, of means controlled by the advanced sheet for arresting the movement of said feed-off devices, and means actuated variably in accordance with the extent of movement of the feed-off devices for controlling and determining the extent of movement of the bank advancing mechanism.

12. In a machine for feeding sheets, the combination with a feed board, mechanism for advancing a bank of feathered sheets upon said feed board including a cam operated lever having a series of control shoulders, means for separating successive sheets from the feathered bank, sheet delivery mechanism, sheet controlled feed-off devices adapted to move successive sheets from the bank to said delivery mechanism, and a dog actuated variably in accordance with the extent of movement of the feed-off devices adapted to engage said lever control shoulders and thereby determine the extent of movement of the bank advancing mechanism.

13. In a machine for feeding sheets, the com-

bination with a sheet support, mechanism for advancing a bank of feathered sheets upon said sheet support, means for separating successive sheets from the feathered bank, sheet delivery mechanism, sheet controlled feed-off devices operating in a plane above said sheet support adapted to move successive sheets from the bank to said delivery mechanism, and means for raising the forward edge of a sheet into the plane of action of said feed-off devices, of means actuated by the movement of said feed-off devices for controlling the bank feeding mechanism.

14. In a machine for feeding sheets, the combination with a sheet support, mechanism for advancing a bank of feathered sheets upon said sheet support, means for separating successive sheets from the feathered bank, sheet delivery mechanism, feed-off grippers operating in a plane above said sheet support adapted to move successive sheets from the bank to said delivery mechanism, and suction grippers for raising the forward edge of a sheet into the plane of action of said feed-off grippers, of means actuated variably in accordance with the extent of movement of said feed-off grippers for controlling the bank feeding mechanism.

15. In a machine for feeding sheets, the combination with a sheet support, mechanism for advancing a bank of feathered sheets upon said sheet support, means for separating successive top sheets from the feathered bank, sheet delivery mechanism, a reciprocating feed-off bar operating in a plane above said sheet support, an automatic sheet engaging gripper mounted upon said feed-off bar and adapted to move successive sheets from the bank to said delivery mechanism, and a suction device upon said feed-off bar for raising the forward edge of a sheet into the plane of action of said automatic gripper, of means actuated variably in accordance with the extent of movement of said feed-off devices for controlling the bank feeding mechanism.

LEONARD H. CROSS.
